COIN SELECTOR

Fred E. Wallin, St. Louis, Mo., assignor to National Slug Rejectors, Inc., St. Louis, Mo., a corporation of Missouri

Application August 7, 1944, Serial No. 548,414

1 Claim. (Cl. 194—102)

1

This invention relates in general to coin selectors and more particularly to an improved device for separating undersize and underweight coins from coins of acceptable diameter and weight. The distinct feature over similar prior inventions is directed to an improved means of greater sensitivity for bypassing or arresting undersize or underweight coins from an acceptance passageway, which means constitutes a principal object of the invention.

A further object of the invention is the provision of a gravity operated means whereby a second deposited coin will not influence or cause a previously arrested coin to be moved to an acceptance passageway.

Further objects and advantages of one embodiment of the invention will be apparent in the following description and drawings in which:

Fig. 1 represents a side elevation of a conventional coin selector.

Fig. 2 is a fragmentary enlarged end view of the coin selector shown Fig. 1 taken through section lines 2—2.

Fig. 3 is a plan view of the selector shown Fig. 1.

Fig. 4 is a fragmentary view of the selector shown Fig. 1 with elements in changed position.

Figs. 5 and 6 show movable elements shown Fig. 1 under two different operating conditions.

Fig. 7 is a perspective view of elements shown in Fig. 5 in normal rest position.

Referring to Fig. 1, a frame 1 is provided for mounting the parts of the selector including a gate 2 pivotally secured to frame 1 by pin 3. The gate 2 provides the hanger for the improved weighing rocker 4 which is pivotally suspended to the gate by stud 5. A pendant counterweight 6 is pivotally secured to the rocker 4 by shoulder screw 7 better shown Figs. 2 and 3. A deposit passageway is formed by a flange 8 of frame 1 and pin 9 secured perpendicularly in the gate 2. An acceptance passageway is formed by the rear wall 10 of frame 1 and the inside surface of gate 2 and a runner 11. The latter is adjustably positioned to the inside surface of gate 2 by screws 12—12.

Referring to Fig. 1, the space in the frame directly beneath the rocker 4 is utilized as a rejection passageway.

This coin selector is of the type utilizing conductivity and impact tests after a coin has been presented to its acceptance passageway. Magnets 13—13 are for general descriptive purposes only and play no part in the improvement herein described.

2

The rocker 4, shown Fig. 1, is provided with an arm 14 terminating in an abutment 15 which projects laterally through an aperture 16 in gate 2, into the space between the rear wall 10 and the gate 2 as shown Fig. 2. A transverse abutment 17 is integral with rocker 4 and spaced a predetermined distance from abutment 15 and projects through aperture 18 into the acceptance passageway. Integral with abutment 17 is a projection 19 which extends in spaced relation between the inside surfaces of the rear wall 10 and the gate 2 as shown Fig. 2. The shape of the rocker 4 and its projections, together with the counterweight 6, is clearly shown Fig. 7.

15 In operation, and assuming that a coin 20, having a diameter less than that of an acceptable coin, is deposited in the entrance passageway (shown Fig. 1) it will descend by gravity between the accurately spaced abutments 15 and 17 respectively, and thence escape downwardly into a rejection passageway.

In the event an underweight coin having a proper diameter is deposited in the entrance passageway, it will descend part way between abutments 15 and 17 and be retained thereby as is illustrated in Fig. 5, for the reason that the coin will not gain sufficient inertia or have sufficient weight to overcome the restraining action of the pendant counterweight 6, and will not move the rocker 4 sufficiently far to pass the coin to the runner 11. It will be noted, as indicated in the drawings, that the moment arm is increased as the rocker pivots from its normal unloaded position. When a coin is so arrested, the gate 2 will necessarily have to be moved by means not shown to displace the arrested underweight coin to a rejection passageway. By reference to Figure 6 it will be noted that a second coin is retained by an arrested coin.

30 Fig. 4 illustrates a coin 21 of acceptable weight and diameter which, when deposited in the entrance passageway, will impinge upon the abutments 15 and 17 and move the rocker 4 about its stud 5 against the restraining action of counterweight 6 to a position where the coin will roll by gravity down the inclined runner 11 to the acceptance passageway. The use of the pendant counterweight 6 is a decided advantage over a

45 fixed counterweight in that the first motion of the rocker is only slightly resisted but further motion is progressively resistant in a gradually increased amount whereas a fixed counterweight would present a relatively high initial inertia, and 55 thus mitigate against extreme sensitivity in elimi-

nating coins having weights very close to the weight of an acceptable coin.

Having described my invention I claim:

In a coin separator, a frame, means forming entrance, acceptance and rejection passageways, a rocker, means pivoting said rocker on said frame at substantially the junction of said passageways, a counterweight and means pivotally mounting said counterweight on one side of a vertical line passing through the pivot of said rocker, said rocker having two spaced abutments projecting into said entrance passageway, the distance between said abutments being sufficient to support a coin of a diameter equal to or greater than a coin of an acceptable diameter and to pass 10 a coin between them of insufficient diameter, the pivot of said counterweight and at least one of said abutments being located on opposite sides of said vertical line passing through the pivot of said rocker to thereby cause pivoting of said 20

rocker and counterweight and permit the passing of said coin into said acceptance passageway and sustain a coin having a weight less than the weight of an accepted coin between said abutments even upon the deposit of a second coin, the other of said abutments having a projection serving to partially support a second coin.
